Application July 29, 1944, Serial No. 547,123

11 Claims. (Cl. 179—15)

1

This invention relates to multi-channel communication systems and more particularly to the selective reception of a plurality of transmitted channels.

One of the objects of this invention is to provide an improved method and means for the selective reception in a multi-channel communication or broadcasting system of a plurality of intelligence conveying channels, the different channels being distinguished by different identifying characteristics.

A further object of the invention is to provide a method and means at the receiving points of a communication system for selectively receiving any one or more of a plurality of signal channels transmitted in time-spaced relation over a common transmission medium, such as a transmission line or a given carrier radio frequency wave.

Another object of the invention is to provide methods and means for selective multi-channel reception, wherein signal intelligence is conveyed over each channel by means of a series of pulses which are modulated with respect to any one of a number of their characteristics such as time position, for example, in accordance with the instantaneous value of the intelligence, and wherein the pulses of the individual channels have different identifying widths.

An additional object of the invention includes the provision of a method and means for the selective reception of the respective channels in multi-channel communication systems in accordance with the characteristic pulse widths thereof.

According to certain features of the invention, a number of channels, conveying signal intelligence by means of a series of pulses, each channel characterized by an identifying pulse width and the pulses of which are modulated with respect to one of their characteristics in accordance with the signal intelligence to be conveyed are received in time-spaced relation as a single train of pulses at the receiving terminal and applied to a pulse-width-to-amplitude-translator. Here, the incoming pulses, having different widths for the various channels, are translated into undulations of similar width, the amplitudes of which are made to vary as the widths of the corresponding pulses. From the translator, the undulations now characterized for each channel by an identifying amplitude may then be fed as a single train of undulations to a peak riding clipper, and to one or more of a plurality of mixer and peak riding clipper circuits, representing the various channels of communication respectively. In the first peak-riding clipper circuit,

2

the undulations having relative maximum amplitude are segregated by clipping a given portion of their amplitude which is amplified and demodulated for recovery of the original signal conveyed over this channel.

The clipped portions, thus obtained from the first peak riding clipper, may also be used to substantially eliminate from the train of undulations, before the train of undulations is applied to subsequent peak riding clipper circuits, which act to successively segregate by clipping of their peak portions, the undulations having relative maximum amplitudes in sequential order according to their values. In order to achieve this effect, the clipped portions of a given channel or channels having relative maximum amplitude undulations, may be first inverted and then mixed with the train of undulations from the original translator or a preceding channel, whereby the first or preceding maximum amplitude undulations are substantially cancelled out. This brings in line for segregation by the peak riding clippers in the subsequent channel circuits the undulations of the channel having the second or succeeding maximum undulations.

This principle may be employed to successively eliminate one channel after another before applying the train of undulations to the peak riding clipper of the next channel.

30 The above and other objects and features of the invention will become more apparent upon consideration of the following detailed description to be read in connection with the accompanying drawings, in which:

35 Fig. 1A is a block diagram of a receiving terminal of a multi-channel communication system according to my invention;

Fig. 1B is a block diagram of a modified form of the receiving terminal of Fig. 1A.

40 Fig. 2 is a schematic circuit diagram of a width-to-amplitude translator and of a peak-riding clipper circuit of the receiving terminal circuits of Fig. 1; and

Fig. 3 is a graphical illustration of the operations of the circuits of Fig. 2.

45 Referring to Fig. 1A, the form of receiving terminal illustrated comprises an adjustable pulse width-to-amplitude translator 1, which feeds in parallel the circuits for the first and second channels. The system, of course, may include a number of additional channels like the third channel shown, each being connected to the preceding channel as shown between the second and third channels. The first channel includes a peak riding clipper 2, the second channel includes a mixer

3 and a peak-riding clipper 4, and the third channel includes a similar mixer 5 and peak riding clipper 6. The output of the peak riding clipper 2 is applied to the mixer 3, mixer 5 receiving the output of mixer 3 and that of the peak riding clipper 4. The outputs of the peak riding clippers 2, 4 and 6 may be applied to demodulators, as desired. A further channel 4, which is not shown, may be similarly supplied from mixer 5 and clipper 6, as indicated.

In Fig. 1B, the receiving terminal is made up of the same major circuit elements as the form of Fig. 1A, except that in this case, the adjustable translator 1 feeds all of the channel circuits in parallel, and the output of the peak riding clippers 2, 4 and 6 are fed into a common connection P, from which the mixers are individually supplied, the various channel circuits being separated by de-couplers D. Further channel circuits, as required, may be similarly connected to the translator 1 and the peak riding clipper connection P.

Fig. 2 illustrates circuit 1 and 2, as shown in block form in Figs. 1A and 1B.

The circuit 1 is utilized for translating a train of pulses of various widths into undulations having corresponding amplitude variations, as described, for instance, in the copending application of E. Labin and myself, Serial No. 487,072, filed May 15, 1943, wherein the circuit is disclosed as a pulse selector according to pulse width.

The circuit includes a limit clipping stage 7 as an input coupler, which limits all input pulses to substantially the same amplitude and, also, inverts the input pulses from a positive polarity, as indicated by the pulses of curve a, Fig. 3, to negative polarity indicated by the pulses of curve b. The output pulse energy from stage 7 is applied through a resistor R to a tuned shock-excitable L.-C. circuit 8. Connected across the tunable circuit 8 is a vacuum tube 9, the cathode 10 of which is connected to the input side of the circuit 8, while its anode 11 is connected to the opposite side 12 of the tunable circuit. The side 12 is also connected to a source of anode potential at 13. The pulse energy, as in curve b, Fig. 3, from an anode connection 14 of the tube 9 is applied to the grid of the tube 9, so as to block conduction between the cathode 10 and the anode 11, while pulse energy is applied to the circuit 8. The undulations, which are produced in circuit 8 in response to pulse energy coming in over connection 14, are taken off through a connection 15 for application to the peak riding clipper stage 2. The undulations in connection 15 are fed over a condenser 16 to a grid 17 of tube 18. The grid circuit includes a resistor 19 and a biasing resistor 20, the latter being shunted by the usual by-pass condenser 21. An anode 22, through a load resistor 23, is connected to the positive end 24 of an anode potential source B⁺ at 13. Potentials developed across resistor 23 are delivered as output to the next stage at connection 27. Branching off from connection 15 is a connection 28 which serves to feed undulations from the width-to-amplitude translator 1 to the circuit of channel 2 as in Fig. 1A, or to the circuit of channels 2, 3 and others as in Fig. 1B.

The operation of the circuits of Fig. 2 will now be described in connection with the curves of Fig. 3.

Assume for the purpose of illustration, the width of the pulses for the three channels in curves a and b to be of the character indicated by the reference characters W₁, W₂ and W₃. As-

sume, also, that circuit 8 is tuned for a maximum response, that is for selection of pulse width W₁. In that case, curve c represents the output of circuit 8 when the circuit is tuned for a maximum response to pulses having the width W₁, illustrating a series of output undulations as obtained from the different pulse widths of curve a. In order to clarify this, it may be mentioned at this point, that when the leading edge of the pulse W₁ is applied at negative polarity, as in curve b, to circuit 8, an initial undulation 29 is produced, which is normally followed by undulations 30 and 31, and so on in the form of a damped wave. When the circuit 8 is tuned to a frequency, the period of which is exactly twice the width W₁, the trailing edge of the W₁ pulse occurs where the initiated oscillatory energy crosses the zero axis from undulation 29 to the undulation 30. Since the trailing edge of this pulse shock-excites the circuit 8 in the same direction at this point, the undulation 32 produced thereby in circuit 8 adds algebraically to the undulation 30 to produce a resultant undulation 33. The next succeeding pairs of undulations produced by the leading and trailing edges of pulse W₁ would normally tend to produce a negative undulation 34, which would tend to continue as a damped wave. Damping tube 9, however, eliminates any such trailing oscillations so that they do not interfere with the undulations produced by subsequent pulses applied to circuit 8.

A pulse width less than pulse width W₁, such, for example, as the width W₃ will not produce undulations as great as undulation 33, if the circuit tuning is adjusted to correspond to pulse width W₁. This is illustrated by undulation 35, produced in response to the pulse width W₃. The reason for this is readily apparent, because shock excitations, produced by the leading and trailing edges of the pulses of lesser width than W₁, will in part be opposed to each other. Undulation 36, in response to the greater pulse width W₂, is likewise smaller than undulation 33, since here again, the oscillations, produced in response to the leading and trailing edges of the greater pulse width, are in part opposed to each other, so that the algebraic summation thereof is less than in the case of undulations produced in response to pulse width W₁.

Curve c of Fig. 3 therefore represents a series of output undulations corresponding to the train of pulses, as in curve a, which are present in the output connection 15, and which may be fed to the peak riding clipper stage 2 and to mixer 3 as in Fig. 1A, or in parallel to all channels as in Fig. 1B.

As the operating characteristics of a peak follower or peak-riding clipper are known in the art, only a brief description of such operation will now be given. If, for example, a positive potential, as represented by the undulation 33 is applied to the side 31 of the condenser 16 (Fig. 2), grid current will flow through resistance 19 charging the condenser 16 and resulting in a negative potential on side 38, thereof. This negative potential is effective on the grid 17, the value of such potential being proportionate to the voltage amplitude of the undulation applied to condenser 16. The parameters of the circuit, represented by condenser 16 and its associated resistor 19, are such that the resultant time constant of the circuit will permit the condenser to lose its charge only very slowly and only to a certain point. The effect of the charge on condenser 16 is to maintain a cut-off bias on the tube 18 at

the level designated by broken line 39, curve *c*, Fig. 3. The charge on the condenser, represented by this line 39, will remain at this level as a steady state condition, since only a small quantity of the charge will be dissipated during the intervals between undulations, and the charge will be kept replenished by each succeeding undulation. The loss of the charge and thereby the cut-off level is, of course, also a function of the repetition rate of the undulations responsible for the establishment of the level. It becomes clear, therefore, that only portion 40 of the undulation 33 appearing above the aforesaid level 39 will be passed by the tube 18, and will appear in its output at 21. The function of such a peak follower or peak riding clipper as at 2, is to tend to clip off a fixed amount from the crest of those applied undulations having maximum amplitude, regardless of the actual amplitude of such undulation. If undulations of lesser amplitude than that represented by the level 39 are applied, such undulations would not be represented in the output because of the peak clipping level line 39 which is established by undulations having a maximum relative amplitude extending above the level 39. This circuit tends, therefore, to select maximum amplitude undulations in each case. The level represented by line 39, as will be now understood, varies with the maximum amplitude of the undulations received, so that, if undulation 33 were eliminated from the series of undulations shown in curve *c*, the undulations having the next maximum relative amplitude, would be those referred to by reference 36 curve *f*, and the clipping level would automatically be established at 41, accordingly. In each case, therefore, the peak clipping level will be established automatically to select the crest of the undulations having a maximum amplitude for a given series of undulations.

This characteristic I make use of by using the clipped peaks of the maximum amplitude undulations to successively eliminate such maximum undulations whereby the peak riding clipper circuit in the subsequent channels are enabled to select undulations having the next highest amplitude, in succession.

The clipped peaks, for instance, of undulation 33, indicated by curve *d*, may be amplified and inverted in the clipper circuit 2, to assume the form as shown in curve *e* which are then mixed at mixer 3 with the series of undulations represented in curve *c*. The resulting series of undulations, as obtained from mixer 3, is shown in curve *f* where it is seen that the undulations 33 have now practically disappeared, and undulations 36 having assumed the role of the maximum amplitude undulation formerly had by undulations 33. It should be noted that since the frequency response characteristic is limited to a practical degree, the sharp peaks which result from this subtraction are considerably reduced in amplitude.

This train of undulations (curve *f*) is applied to the peak riding clipper circuit 4, Fig. 1A, where, automatically, a clipping level 41 is established curve *f*, and the peaks 42 of the undulations 36 are clipped off as shown in curve *g*. This output is analogous to that obtained from peak riding clipper 2 for channel 1, and may be similarly used to obtain a reproduction of the original signal for channel 2 by demodulation. Portions 42 may also be used to eliminate undulations 36 by inversion and mixing in mixer 5 with the output of mixer 3. This enables peak riding clipper 6 in the circuit of channel 3 to establish

automatically a peak clipping level corresponding to undulations 35, which have now come to be the maximum amplitude undulations in the series applied to clipper 6.

In the form of the circuit arrangement shown in Fig. 1B, the successive elimination of the maximum amplitude undulations of preceding channels is obtained by mixing the original series of undulations (curve *c*) with the cumulative output of all the preceding peak riding clippers by feeding the output of these clippers into the common line *P*, and deriving therefrom the combined output of the preceding clippers, as shown for clippers 2 and 4 in curve *h*. As this combined output of the preceding clippers is mixed with the original undulations (curve *c*), the undulations 33 and 36 are reduced to negligible size and the clipper 6 receives the remaining undulation 35 to act on. The decouplers *D* between channels serve to prevent the feedback of the clipper output toward the preceding channels.

Further similar clipping and mixing operations may be employed to obtain the separation of the undulations of additional channels.

It will be apparent that by varying the tuning of the resonant circuit 8 for effective maximum response to other pulse widths, the sequence of the selection of the channels may be changed at will, if desired.

It is thus seen that by a combination of the circuits hereinabove described, an effective pulse width selector has been provided, in accordance with the objects set forth heretofore.

While I have described above the principles of this invention in connection with specific apparatus, it is to be clearly understood that this description is made only by way of example, and not as a limitation on the invention and the scope of accompanying claims.

40 I claim:

1. A method of selectively receiving a plurality of channels of communication from a multi-channel train of pulses wherein the pulses of each channel differ from pulses of other channels by a different identifying width; comprising translating said pulses into a series of corresponding undulations the amplitudes of which vary substantially as the respective width of the corresponding pulses; and successively selecting 45 the undulations of each channel in accordance with the relative values of the amplitudes thereof.

2. A method according to claim 1, wherein the operation of translating includes the steps of establishing a resonating condition in accordance 50 with a desired sequence of the channels to be selected.

3. A method according to claim 1, wherein the operation of translating includes the steps of producing periodic oscillations by means of said pulses under conditions of resonance at a frequency having a period proportionate to the width of the pulses of a given first channel.

4. A method according to claim 1, wherein the operation of selecting includes the steps of successively clipping the peaks of the undulations in the order of the values of the amplitudes thereof.

5. A method of selectively receiving a plurality of channels of communication from a multi-channel train of pulses wherein the pulses of each channel differ from pulses of other channels by a different identifying width; comprising translating said pulses into a series of corresponding undulations the amplitudes of which vary substantially as the respective width of the corresponding pulses; and selecting the undulations

of a given channel by successive maximum peak clipping the undulations of the channels having the larger amplitudes, employing the resultant of said maximum peak clipping operation to eliminate said undulations having the larger amplitudes from the said series, and maximum peak clipping the maximum amplitude undulations thus obtained.

6. A method of selectively receiving a channel of communication from a multi-channel train of pulses wherein the pulses of each channel differ from pulses of other channels by a different identifying width; comprising translating said pulses into a series of corresponding undulations the amplitudes of which vary substantially as the respective width of the corresponding pulses; and selecting the undulations of a given channel by maximum peak clipping the undulations of the channels having the larger amplitudes; inverting, amplifying and mixing the resultant of said maximum peak clipping operations with the said series of undulations representing all the channels, and maximum peak clipping the maximum amplitude undulations thus obtained.

7. A method of selectively receiving a plurality of channels of communication from a multi-channel train of pulses wherein the pulses of each channel differ from pulses of other channels by a different identifying width; comprising translating said pulses into a series of corresponding undulations of the amplitudes of which vary substantially as the respective width of the corresponding pulses; and selecting the undulations any of said channels by successive maximum peak clipping the undulations of the channels preceding those of any given channel with respect to their amplitude values; mixing the train of undulations obtained for the channel immediately preceding any given channel, before said train has been subjected to maximum peak clipping, with the inverted and amplified output of the maximum peak clipping operation as applied to said preceding channel, and maximum peak clipping the series of undulations thus obtained.

8. A multiplex system for selectively and simultaneously receiving any of a number of channels of communication from a multi-channel train of pulses wherein the pulses of each channel differ from pulses of other channels by a different identifying width; comprising means for translating said pulses into a series of corresponding undulations the amplitude of which vary substantially as the respective width of the corresponding pulses common to all channels; and for each channel, means for selecting from said series the undulations of a given channel in

accordance with the relative amplitude thereof.

9. A system according to claim 8, wherein said means for translating includes a resonant circuit tuned to a frequency having a period proportionate to the width of the pulses of a given first channel.

10. A system for selectively receiving a plurality of channels of communication from a multi-channel train of pulses wherein the pulses of each channel differ from pulses of other channels by a different identifying width; comprising means for translating said pulses into a series of corresponding undulations the amplitudes of which vary substantially as the respective width of the corresponding pulses, including a resonant circuit tuned to a frequency having a period proportionate to the width of the pulses of a given first channel, a plurality of receiving channels each having circuit means for selecting the undulations of a channel when the undulations thereof are of maximum amplitude, including peak-rider clipping means in each receiving channel, and mixer means in all but the first receiving channel; means for applying said series of undulations to the circuit means of the first and second receiving channels; and means for applying the output of the circuit means of each receiving channel to the mixing means of the succeeding receiving channel.

11. A system for selectively receiving a plurality of channels of communication from a multi-channel train of pulses wherein the pulses of each channel differ from pulses of other channels by a different identifying width; comprising means for translating said pulses into a series of corresponding undulations the amplitudes of which vary substantially as the respective width of the corresponding pulses, including a resonant circuit tuned to a frequency having a period proportionate to the width of the pulses of a given channel; a plurality of receiving channels each having circuit means for selecting the undulations of a channel where the undulations thereof are of maximum amplitude, including peak rider clipping means in each receiving channel, and mixer means in all but the first channel; means for applying said series of undulations to each of said channel circuit means; means for receiving the output of the circuit means of each of the channels separated into channel sections; and means for applying the cumulated output of the preceding circuit means to the mixer means of a given channel.
